(57) **CLAIM**

The ornamental design for a coordinate input instrument, as shown and described.

DESCRIPTION

FIG. 1 is a perspective view of a coordinate input instrument according to my new design;

FIG. 2 is a top plan view of the coordinate input instrument of FIG. 1;

FIG. 3 is a front view of the coordinate input instrument of FIG. 1, the rear view of the coordinate input instrument being mirror symmetrical;

FIG. 4 is a bottom view of the coordinate input instrument of FIG. 1;

FIG. 5 is a left side view of the coordinate input instrument of FIG. 1; and,

FIG. 6 is a right side view of the coordinate input instrument of FIG. 1.

The broken lines show portions of the coordinate input instrument which form no part of the claimed design.
